SERVING TRAY FOR PIZZA

Brian C. Egan, 230 E. Ontario,
Chicago, Ill. 60611

Filed Sept. 20, 1972, Ser. No. 290,443

Term of patent 7 years

Int. Cl. D7—01

U.S. Cl. D7—21

FIG. 1

FIG. 2

FIG. 3

FIG. 1 is a right or left side elevation of a serving tray for pizza showing my new design;

FIG. 2 is a front or rear elevation thereof;

FIG. 3 is a top view thereof; and

FIG. 4 is a bottom view thereof.

I claim:

The ornamental design for a serving tray for pizza, as shown.
